KERF-CUTTING MACHINE

William W. Sloane, Chicago, Ill., assignor to
Goodman Manufacturing Company, Chicago,
Ill., a corporation of Illinois

Original application June 5, 1936, Serial No.
83,733. Divided and this application January
11, 1937, Serial No. 119,925

14 Claims. (Cl. 262—28)

The principal object of my invention is to provide a novel form of power driven means for adjustably moving the cutter bar toward and from a supporting frame, which adjusting means also equalizes the loads between the supporting frame and cutter bar and serves to hold the cutter bar in substantially parallel relation with respect to its supporting frame during adjustment and cutting.

10 Other objects of my invention will appear from time to time as the following specification proceeds.

This application is a division of a prior application Serial No. 83,733 filed June 5, 1936, now Patent No. 2,118,529, granted May 24, 1938.

15 My invention may be more clearly understood with reference to the accompanying drawings wherein:

Figure 1 is a fragmentary plan view of the 20 forward portion of a mining machine constructed in accordance with my invention, with parts of the gear covers broken away and certain other parts shown in horizontal section in order to illustrate certain details of my invention;

25 Figure 2 is a fragmentary longitudinal sectional view of the forward portion of the machine shown in Figure 1 drawn to an enlarged scale;

Figure 3 is a detail view of the opposite side of the forward portion of the machine than is 30 shown in Figure 2 and showing certain parts broken away and in longitudinal section which are not shown in Figure 2;

Figure 4 is a detail partial fragmentary transverse sectional view showing certain details of 35 the cutter bar adjusting mechanism;

Figure 5 is a detail partial fragmentary transverse sectional view showing certain other details of the cutter bar adjusting mechanism not shown in Figure 4;

40 Figure 6 is a detail partial fragmentary sectional view taken substantially along lines 6—6 of Figure 3, showing certain details of the cutter bar adjusting mechanism not shown in Figures 4 and 5;

45 Figure 7 is an enlarged fragmentary sectional view taken substantially along line 7—7 of Figure 1;

50 Figures 8 and 9 are diagrammatic views in side elevation, showing the cutter bar positioned for cutting horizontal kerfs at various elevations with respect to the ground; and

Figure 10 is a diagrammatic view in plan showing the cutter bar positioned for cutting a shearing kerf.

55 In the drawings the embodiment of my inven-

tion illustrated includes a track mounted truck 10 having a cutting element 11 mounted thereon in a pair of parallel-spaced guides 12, 12 for vertical adjustment with respect thereto.

The cutting element 11 includes generally a 5 motor 13 having truck driving mechanism disposed rearwardly thereof and having cutting mechanism disposed forwardly thereof. Said cutting mechanism includes a projecting cutter bar 16 supported by a support frame 15 secured to 10 and projecting from the forward end of said motor.

The cutting mechanism support frame 15 has a projecting forward end 17, a portion of which end depends from said truck and forms a longitudinal pivotal bearing support for a turning frame 18 which projects forwardly from said forward end. Said turning frame has a support frame 19 mounted for rectilinear movement with respect thereto in a plurality of parallel planes 20 in a manner which will hereinafter more clearly appear as this specification proceeds.

A cutter frame 20, which forms a support member for the cutter bar 16, is pivotally mounted in the support frame 19 for pivotal movement about 25 an axis perpendicular to the longitudinal axis of the machine. Said cutter bar has a cutter chain 21 movable thereabout in a closed orbital path, which meshes with a sprocket 22 mounted on a sleeve 23 journaled in said cutter frame coaxial 30 with the pivotal axis thereof in suitable ball bearings. (See Figure 2.)

The cutter chain 21 is driven from the forward end of the motor 13 through a suitable extensible drive connection which includes a splined shaft 24 slidably engaging an internally splined bore of the sleeve 23, and an internally splined hub 25 of a bevel gear 26. Said bevel gear is driven from a bevel pinion 27 on the forward end of a longitudinally extending shaft 28. Said shaft is driven from a longitudinally extending shaft 29 coaxial with the axis of the turning frame 18, by means of a gear train, generally indicated by reference character 30. The drive from the motor to said last-mentioned shaft includes 45 a spur gear 31 on a shaft 32 aligned with the shaft 29, which meshes with a pinion 33 on the forward end of the shaft for the motor 13. Clutch mechanism generally indicated by reference character 34, is provided for selectively connecting 50 said shafts together. Said clutch mechanism is not herein described in detail since it is no portion of my present invention.

The turning frame 18 is mounted on the frame 15 for movement about a longitudinally extend-

ing axis by means of a rearwardly disposed annularly shouldered portion 55 formed integral with said turning frame. Said annular shouldered portion is journaled within a cylindrical inner periphery of the forward end 17 of the cutting mechanism support frame 15. The rear end of said annular shouldered portion abuts an annular bearing member 56, and a forward shouldered portion thereof is journaled in a shouldered bearing member 57. An annular ring 58 is secured to the forward end of the portion 17 and abuts the shouldered bearing 57 for retaining said bearing and the frame 15 in position.

15 A spur ring gear 59 is mounted on the rear end of the annular shouldered portion 55 and abuts the annular bearing 56. Said ring gear is meshed with a spur pinion 60 (see Figure 4), which pinion is on the forward end of a longitudinal 20 extending shaft 61. Said shaft is journaled in the cutting mechanism support frame 15 in a suitable manner and is driven from a transversely extending shaft 63 by means of a suitable worm and worm gear drive, generally 25 indicated by reference character 64. Said worm and worm gear are of the self-locking type arranged to hold the turning frame 18 in the desired position until positively locked, in a manner which is no part of my present invention so 30 is not herein shown or described. A spur gear 65 is keyed on the inner end of the shaft 63 and is adapted to be selectively driven from the motor 19 by means of a novel arrangement of gearing which will not herein be described since it is 35 no portion of my present invention.

35 no portion of my present invention.

Referring now particularly to the mechanism for moving the support frame 19 toward or from the turning frame 18 in parallel relation with respect thereto and equalizing the loads between

40 said frames, said support frame is provided with a pair of parallel-spaced guides 76, 76 extending from the rearward end thereof. Said guides register for engagement with parallel-spaced guides 77, 77 extending from the turning frame

45 18 immediately forwardly of the annular shouldered portion 55. Said adjusting mechanism includes a novel parallel link arrangement disposed forwardly of the guides 77, 77 and having connection with opposite sides of the forward

50 and rearward portions of the support frame 19. A pair of bell crank members 78, 78 are pivotally mounted on opposite sides of the forward end of the turning frame 18 on a transversely extending shaft 79. Another pair of bell crank

55 members 80, 80 are mounted adjacent the rearward end of said turning frame on the outer sides thereof and forwardly of the guides 77, 77 on aligned oppositely extending transversely disposed stud shafts 81, 81. The bell crank members 78, 78 and 80, 80 are connected together to operate as a unit by means of parallel links 82, 82 pivotally connected to lever arms 84, 84 and 85, 85 respectively of said bell crank members.

60 Thus, all of said bell crank members may rock together as a unit in parallel relation with respect to each other upon rocking movement of the shaft 79.

65

70 A second lever arm 87 of each bell crank member 78 is pivotally connected to the forward end of the supporting frame 19 by means of a link 88 extending downwardly therefrom. In a like manner, a second lever arm 91 of each bell crank member 80 is pivotally connected with a rearward portion of the supporting frame 19 by

means of a link 92 which depends from said lever arm in parallel relation with respect to the link 88.

The transversely extending shaft 79 is rocked to move the supporting frame 19 in parallel relation with respect to the turning frame 18 by means of a crank arm 93 secured to said shaft and herein shown as extending upwardly and angularly rearwardly therefrom, when the parts are in the position shown in Figures 1, 2 and 3. Said crank arm has a pair of parallel-spaced rearwardly extending links 95, 95 pivotally connected to opposite sides thereof on the ends of a pin 94. The rearward ends of said links are pivotally connected to stud shafts or pivotal pins 96, 96 extending outwardly from opposite sides of a nut 97. Said nut is threaded on a threaded shaft 98 which is journaled at its rearward end in a guide frame 99 on suitable ball bearings 100, 100. Said shaft extends forwardly along and between the upper and lower sides of a guide 101 formed in said guide frame, and said nut is guided for movement along said guide. (See Figures 1, 3 and 6.) Said guide frame is mounted on and extends along the turning frame 18 in such a manner that the guide 101 is spaced above the bottom of said frame.

Suitable means are provided on the threaded shaft 98 for engaging and holding the nut 97 from movement at the extreme ends of its path 30 of travel along said shaft which as herein shown comprise a stop 105 mounted adjacent the forward end of the front ball bearing 100, and a stop 106 at the forward end of said shaft. Said stops are adapted to engage suitable jaws 108, 108 35 extending forwardly and rearwardly from the nut 97 and thus form a means for locking the shaft 98 from rotatable movement.

A spur gear 103 is secured to the rearward end of the threaded shaft 98 for driving said shaft. Said spur gear is meshed with a spur gear 109 freely mounted on the forward end of a longitudinally extending shaft 110. Said last-mentioned shaft is driven by a spur gear 111 on the rearward end thereof, which is selectively connectible with the forward end of the motor 13, so that it may be driven therefrom in reverse directions without reversal of said motor independently of movement of the other parts of the machine. A suitable slip clutch 113 of the pin type, loaded by means of a spring 114 in a usual manner is provided to connect the gear 109 with the shaft 110. Said clutch is of a construction well known to those skilled in the art and is arranged to slip upon a predetermined load on the shaft 110 or when the nut 97 engages either of the stops 105 or 106, to prevent breakage of the parts, and is not herein described in detail since it is no portion of my present invention.

The gear 111 and threaded shaft 98 are selectively driven from the forward end of the motor 13, in reverse directions without reversal of said motor, by means of a transversely extending shaft 134 which is journaled in the frame 15. A 65 pair of oppositely disposed bevel gears 135, 135 freely mounted on said shaft are meshed with a bevel gear 136 on the forward end of a longitudinal shaft 137. Said longitudinal shaft is journaled in the cutting mechanism support frame 15 70 and is driven from a spur gear 139 which is meshed with the motor pinion 33.

Suitable friction clutches 143, 143, of a usual construction are provided for connecting either of the bevel gears 135, 135 with the shaft 134 for 75

reversely driving said shaft. Said clutches are shifted to be engaged with said associated bevel gears by means of a clutch collar 144 which is shifted along said shaft by means of a suitable system of levers in a manner not herein shown or described since it is no part of my present invention.

A worm 180 is mounted on the transversely extending shaft 134 and meshes with a worm gear 181 keyed on a longitudinally extending sleeve 182 journaled in the frame 15. (See Figure 6.) Said sleeve extends within a planetary gear reduction mechanism 183, and, as herein shown, has a pinion 184 cut integral therewith which 15 serves as a sun gear and drive means for said planetary. Said planetary is of a construction which is clearly shown and described in my parent application of which this is a division so will not herein be described in detail. The sun gear 20 184 meshes with planetary pinions 185, 185 mounted in a cage 187. Said planetary pinions mesh with an internal gear 188. Planetary pinions 189, 189 are disposed coaxial with and are rotatable with the planetary pinions 185, 185 and 25 mesh with an internal gear 190 which is secured to a shaft 193. The cage 187 is held from rotation by means of a friction band 195 to permit said shaft to be driven at a relatively high rate of speed through a geared reduction which 30 includes the sun gear 184, planetary pinions 185, 185, planetary pinions 189, 189 and internal gear 190. When it is desired to drive the shaft 193 at a low rate of speed, the friction band 195 is released from the cage 187 and a friction band 35 196 is provided, which holds the internal gear 188 from rotation. Thus the shaft 193 and internal gear 190 will be driven through the sun gear 184 and planetary pinions 185, 185 and 189, 189, moving in an orbital path about the internal 40 gear 188.

A spur gear 199 is keyed on the outer end of the shaft 193 and meshes with and drives an idler gear 200. The faces of the teeth of said idler gear are relatively long and said idler gear is 45 adapted to mesh with a spur gear 201 feathered on a sleeve 202 for movement therealong. Said sleeve is journaled on the longitudinally extending shaft 29 which is disposed coaxial with the turning axis of the turning frame 18. A spur gear 204 is keyed on the hub of the spur gear 201 and is adapted to mesh with either the spur gear 111, for moving the cutter bar toward or from the turning frame 18, or a spur pinion 133, for swinging the cutter bar at either a frictionally 50 controlled high positioning or low feeding speed.

It will be seen from the foregoing that a power drive has been provided for selectively driving the threaded shaft 98 in reverse directions without reversal of the motor 13 in a simplified manner independently of the other operations of the machine; that said shaft serves to adjustably move the cutter bar toward or from the turning frame 18 by means of a simplified arrangement of links and levers which serve to equalize the 55 loads between the forward and rearward ends of the support frame 19 and to prevent binding between the guides 76, 76 and 77, 77; and that said mechanism is confined substantially within the limits of the turning frame 18 when the parts 60 are in a retracted position.

While I have herein shown and described one form in which my invention may be embodied, it will be understood that the construction and arrangement of the parts may be altered without departing from the spirit and scope of my 65

invention. I do not, therefore, wish to be understood as limiting myself to the specific construction illustrated herein, excepting as specifically limited in the appended claims.

I claim as my invention:

1. In a mining machine, a base, a frame extending forwardly therefrom, a projecting cutter bar supported for movement towards and from said frame, and means for supporting said cutter bar and moving it towards and from said frame comprising a parallel link connection between said frame and cutter bar and power driven means for moving said links in parallel relation with respect to each other including a rocking member, an extensible member connected 15 with said rocking member for rocking said rocking member, and an operative connection between said rocking member and said parallel link connection.

2. In a mining machine, a base, a frame extending forwardly therefrom, a pair of parallel spaced guides projecting from said frame, a projecting cutter bar guided for movement towards and from said frame in said guides, and power operated means for supporting said cutter bar and moving it towards and from said frame comprising a parallel link connection between said frame and cutter bar disposed forwardly of said guides, and power-driven means for moving said links in parallel relation with respect to each 20 other including an extensible drive member, and an operative connection between said member and said parallel links.

3. In a mining machine, a base, a frame extending forwardly therefrom, a projecting cutter bar supported for movement towards and from said frame, and means for supporting said cutter bar and moving it towards and from said frame comprising a parallel link connection between said frame and cutter bar including a pair 25 of spaced parallel links connected to each side of said frame, and power driven means for moving said links in parallel relation with respect to each other comprising a threaded shaft rotatably driven by power, a nut thereon and movable therealong, and an operative connection from said nut to said links.

4. In a mining machine, a base, a frame extending forwardly therefrom, a projecting cutter bar supported for movement towards and from said frame, and means for supporting said cutter bar and moving it towards and from said frame comprising a parallel link connection between said frame and cutter bar including a pair 30 of spaced parallel links connected to each side of said frame, and power driven means for moving said links in parallel relation with respect to each other comprising a threaded shaft rotatably driven by power, a nut thereon and movable therealong, and an operative connection from said nut to said links including a transverse torsion shaft, a crank arm on said shaft, a connection from said nut to said crank arm for pivoting said shaft upon translational movement of said nut, and an operative connection from said shaft 35 to said links.

5. In a mining machine, a base, a frame extending forwardly therefrom, a projecting cutter bar supported for movement towards and from said frame, and power-driven means for moving said cutter bar towards or from said frame comprising a threaded shaft rotatably driven by power, a nut thereon and movable therealong, a transverse torsion shaft, a crank arm on said shaft, a connection from said nut 40 to said shaft.

- to said crank arm for pivoting said shaft upon translational movement of said nut, a pair of bell crank members on opposite ends of said shaft, a linkage connection between one lever 5 arm of each of said bell crank members and said cutter bar, another pair of bell crank members spaced rearwardly of said first-mentioned bell crank members and movable in parallel relation with respect thereto, a linkage connection between the other lever arms of said first-mentioned bell crank members and said second-mentioned bell crank members, and a linkage connection between the other lever arms of said second-mentioned bell crank members and said cutter bar.
6. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said frames in parallel relation with respect to each other, and adapted to prevent binding between said guides and cutter frame during such movement, said equalizing connection being disposed forwardly of said guides for moving said cutter frame towards and from said support frame and comprising a torsion shaft disposed transversely of said frame and pivotally moved by power, and a parallel link connection from said torsion shaft to said cutter frame.
7. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said frames in parallel relation with respect to each other and adapted to prevent binding between said guides and cutter frame during such movement, said equalizing connection being disposed forwardly of said guides and comprising a torsion shaft disposed transversely of said frame and pivotally moved by power, and a parallel link connection from said torsion shaft to said cutter frame including a pair of bell crank members disposed adjacent the forward end of said cutter frame, another pair of bell crank members spaced rearwardly therefrom, a link connecting each pair of said bell crank members together to operate as a unit, and links connecting the other lever arms of said bell crank members with said cutter frame.
8. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said cutter frame towards and from said support frame adapted to prevent binding between said guides and cutter frame during such movement, and comprising a torsion shaft disposed transversely of said frame adjacent the forward end thereof, rocking members on opposite ends of said shaft and rocked thereby, another pair of rocking members disposed adjacent to but forwardly of said guides, a connection between said first and second-mentioned rocking members and a parallel link connection between said rocking members and said cutter frame whereby pivotal movement of said shaft will move said cutter frame towards or from said first-mentioned frame in parallel relation with respect thereto.
9. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said cutter frame towards and from said support frame and adapted to prevent binding between said guides and cutter frame during such movement, said equalizing connection comprising a torsion shaft disposed transversely of said frame adjacent the forward end thereof, rocking members on opposite ends of said shaft and rocked thereby, another pair of rocking members disposed adjacent to but forwardly of said guides, a connection between said first and second-mentioned rocking members, a connection between said rocking members and said cutter frame, and power-driven means for pivotally moving said torsion shaft comprising a threaded shaft rotatably driven by power, a nut on said threaded shaft, and a connection from said nut to said torsion shaft.
10. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said cutter frame towards and from said support frame and adapted to prevent binding between said guides during such movement, and comprising a torsion shaft disposed transversely of said frame adjacent the forward end thereof, rocking members on opposite ends of said shaft and rocked thereby, another pair of rocking members disposed adjacent to but forwardly of said guides, a connection between said first and second-mentioned rocking members, a connection between said rocking members and said cutter frame, and power driven means for pivotally moving said torsion shaft comprising a nut movable longitudinally of the machine, an operative connection between said nut and torsion shaft and a threaded shaft rotatably driven by power, extending longitudinally of said frame and threaded within said nut.
11. In a mining machine, a base, a frame extending forwardly therefrom, a cutter frame having a cutter bar projecting therefrom, a pair of parallel-spaced guides engaging the rearward end of said cutter frame, and a power driven equalizing connection between said frames for moving said cutter frame towards and from said support frame and adapted to prevent binding between said guides during such movement, and comprising a torsion shaft disposed transversely of said frame adjacent the forward end thereof, rocking members on opposite ends of said shaft and rocked thereby, another pair of rocking members disposed adjacent to but forwardly of said guides, a connection between said first and second-mentioned rocking members, a connection between said rocking members and said cutter frame, and power driven means for pivotally moving said torsion shaft comprising a guide extending longitudinally of said frame, a nut guided for movement along said guide, an operative connection between said nut and torsion shaft, and a threaded shaft rotatably driven by power, extending along said guide and having said nut threaded thereon.
12. In a mining machine, a base, a frame extending forwardly therefrom, a cutter frame having a cutter bar projecting therefrom, a pair of parallel-spaced guides engaging the rearward

end of said cutter frame, and a power driven equalizing connection between said frames for moving said cutter frame towards and from said support frame and adapted to prevent binding 5 between said guides during such movement, and comprising a torsion shaft disposed transversely of said frame adjacent the forward end thereof, rocking members on opposite ends of said shaft and rocked thereby, another pair of rocking 10 members disposed adjacent to but forwardly of said guides, a connection between said first and second-mentioned rocking members, a connection between said rocking members and said cutter frame, and power driven means for pivotally 15 moving said torsion shaft comprising a guide extending longitudinally of said frame, a nut guided for movement along said guide, an operative connection between said nut and torsion shaft, and a threaded shaft journaled at one 20 end of its ends and having the free portion thereof extending along said guide and having said nut threaded thereon.

13. In a mining machine, a base, a frame, a projecting cutter bar, and means for supporting

said cutter bar and moving it towards and from said frame including a pair of parallel links arranged on each side of said frame and having connections with said frame and cutter bar, a rocking member, an operative connection between 5 said rocking member and each pair of parallel links, and a member extensibly movable along said frame for rocking said rocking member and holding it from rocking movement.

14. In a mining machine, a base, a frame, a 10 projecting cutter bar, and means for supporting said cutter bar and moving it towards and from said frame including a pair of parallel links arranged on each side of said frame and having connection with said frame and cutter bar, a 15 rocking member, an operative connection between said rocking member and each pair of parallel links, means for rocking said rocking member and holding it from rocking movement including a member guided for extensible movement along said frame and power driven means for extensibly moving said member along said 20 frame.

WILLIAM W. SLOANE.
